UNITED STATES PATENT OFFICE.

JOHN G. CALLAN, OF LYNN, MASSACHUSETTS, ASSIGNOR TO GENERAL ELECTRIC COMPANY, A CORPORATION OF NEW YORK.

ELASTIC-FLUID TURBINE.

No. 845,448.

Specification of Letters Patent.

Patented Feb. 26, 1907.

Application filed September 15, 1904. Serial No. 224,532.

To all whom it may concern:

Be it known that I, JOHN G. CALLAN, a citizen of the United States, residing at Lynn, county of Essex, State of Massachusetts, have invented certain new and useful Improvements in Governing Mechanism for Elastic-Fluid Turbines, of which the following is a specification.

The present invention relates to governing mechanisms which automatically admit energy to or cut it off from a prime mover in accordance with changes in load, and more specifically to elastic-fluid turbines.

The object of my invention is to provide a governing mechanism of improved construction wherein all uncertainty of the valves or other regulating devices operating in the proper manner is obviated and this without undue load on the speed-responsive device.

The invention can be used in connection with valves of original admission or with valves between stages or with both. It is also capable of other uses.

In carrying out my invention a fluid under pressure is employed as the motive agent for opening and closing the admission or regulating valves, and this fluid is preferably, but not necessarily, non-compressible. The fluid is continually circulating through the system, and while its pressure may momentarily vary somewhat with changes in position of the valve-operating mechanism the flow for a given time interval remains constant. The

fluid which operates the valves is or may be employed for another purpose—such, for example, as lubricating one or more bearings. Oil, water, or other fluid may be employed for this purpose. The system may be said to be a "series" system wherein the fluid dis-

charged by a pump, accumulator, or equivalent device first passes through the valve-actuating mechanism and then through the bearings, the exhaust from which is or may be returned to the source of supply. While

I prefer the so-called "series" system, my invention is not to be construed as being limited thereto, since it is capable of broader application. For example, the valve may be so arranged that fluid supplied from a source under pressure is admitted by a valve closed in its neutral position and opening, and hence using fluid only when the governor moves it from this position and the actuating-piston is to be moved.

The valves are operated by a fluid-actuated motor through suitable means so arranged that they open and close successively or in any predetermined sequence. The valves are arranged in groups, each group being connected directly or indirectly to an actuating-lever, and the latter is connected to an actuator or motor. I have shown only two groups of valves; but it is to be understood that additional groups may be employed. Only one motor is shown in the present embodiment of the invention; but it may be duplicated *ad libitum* and controlled by the speed-responsive device. Where more than a single motor is employed, one or more additional groups of valves will be provided.

Suitable means are provided to insure the successive or otherwise predetermined opening and closing of the valves. In some cases a difference in leverage may be arranged between the actuator and the members of one group of valves, so that the valve subjected to the greatest leverage will open first. In other cases the leverage between the actuator and the valves may be equal, in which case a mechanical or selective means is or may be employed to insure the proper operation of the valves. I may also rely wholly or in part upon the pressure of the motive fluid supplied to the turbine or prime mover to hold one or more valves in a given position while one or more other valves are held in a different position.

As before stated, a fluid-actuated motor performs the actual work of moving the valves, while the controlling-valve for the motor is moved by a speed-responsive device, the latter being either mounted on the turbine-shaft or driven thereby through a power-transmitting device. Since the controlling valve or valves is or are the only parts moved by the speed-responsive device, it follows that the load on the latter is very small. Hence the efficiency of the governing mechanism as a whole will be high.

When the motor-controlling valve is in its normal position, the fluid flows freely into and out of the motor-cylinder and around the valve. Moving the valve in one direction or the other to close or otherwise modify the passage conveying fluid into the cylinder will start the motor-piston into action. As the piston moves in one direction or the other a quantity of liquid from the cylinder is dis-

charged into the pipe leading to the bearing or bearings, which quantity bears a direct relation to the movement of the piston. For a given amount discharged from the cylinder 5 a corresponding amount is admitted and in the same interval of time. Hence there is no fluctuation in the volume of fluid flowing to the bearing or bearings. This is of special advantage, since it prevents fluctuations in 10 the supply of lubricant to the bearings. Where the fluid passing through the motor flows directly to the exhaust, this is not of such controlling importance. It is best, however, to use the same fluid for actuating 15 the motor and lubricating the bearing or bearings, since by so doing only a single source of relatively high pressure-fluid is necessary. It is to be understood, however, that separate sources of fluid-pressure may 20 be used, and many of the advantages of my improved mechanism will follow. Instead of the fluid passing through the motor and bearing in series, it may under certain conditions pass through them in multiple, and certain of 25 the claims are to be construed as being broad enough to include this.

In the accompanying drawings, which illustrate one embodiment of my invention, which has been found to be satisfactory, Figure 1 is 30 a view, partly in section and partly in elevation, of an elastic-fluid turbine of the Curtis type provided with my improved governor. Fig. 2 is a detail view, partly in section, of the valves employed to control a supply of fluid to the bucket wheel or wheels of a turbine. Fig. 3 is a partial end view of a machine, showing the valve-chest broken away to expose the position and arrangement of the valve-seats. Fig. 4 is an axial section of the 35 motor for positively opening and closing the individual nozzle-valves, said section being taken on line 4-4 of Fig. 6. Fig. 5 is a similar view, but taken on line 5-5 of Fig. 6. Fig. 6 is a cross-section of the motor, taken on the line 6-6 of Fig. 4. Fig. 7 is a detail view showing the ball-and-socket joint between the motor-piston and the valve-actuating levers. Figs. 8 to 12, inclusive, are diagrammatic 40 representations of the valves as they appear in different positions of operation. Fig. 13 is a detail view, on an enlarged scale, showing a pair of valves and a means for insuring their closing in the proper manner. Fig. 14 is a view of the same valves taken at right angles to that of the previous figure. Fig. 15 is a 45 detail view, on an enlarged scale, of the motor and its controlling-valve. Fig. 16 is a cross-sectional view through the piston-rod taken on line 16-16 of Fig. 15. Figs. 17 to 21, inclusive, are detail views showing mechanical means for insuring the proper operation of the valves regardless of whether or not the valve-chest is subjected to the pressure of steam or other motive fluid. Fig. 22 is a 50 diagrammatic view showing the invention

applied to a vertical turbine, wherein the same fluid that actuates the motor is employed to lubricate the step-bearing. Fig. 23 is a detail view of the motor-actuated lever and piston-rod. Fig. 24 is a detail view 70 showing valves of different areas, and Fig. 25 is a view of part of a gear-pump for supplying liquid to the motor.

Referring to Fig. 1, 1 represents the main shaft of a turbine that is mounted in bearings 2, only one of which is shown. The shaft extends through the bearings and on its outer end is provided with a speed-responsive device—such, for example, as the one shown in a prior application of myself and Frederic R. C. Boyd, Serial No. 197,788, filed March 12, 1904. It is to be understood that the character of the actuating device for the valve mechanism can be widely varied without departing from the spirit of my invention. As the speed of the shaft changes motion is transmitted from the speed-responsive device through the link 4 to the lever 5, the latter being pivotally supported by the hood 3 or other support. Mounted on the main shaft are one or more wheels 6, provided with buckets 7 of suitable formation. These buckets may be formed on the periphery or on the side face of the wheel or in any other suitable manner and are adapted to 95 impart rotary motion to the shaft. One, two, or more rows of wheel-buckets can be provided. Where two or more rows are provided in one stage, intermediate buckets covering a greater or less area of the wheel-buckets should be provided. The wheel or wheel-buckets are inclosed by a casing or shell 8, that is provided with a hub-like projection 9, containing a packing for preventing the motive fluid in the shell or casing from 100 escaping. Mounted in the right-hand side of the casing is a sectionalized nozzle 10 of improved construction. This nozzle is provided with a plurality of closely-associated passages which have the same angle of delivery and the same degree of expansion where expansion is necessary. It may make these passages expanding or non-expanding in character, depending upon the conditions of service. Bolted or otherwise secured to 105 the nozzle is a plate 11, Fig. 2, having a plurality of orifices, which orifices register with or supply fluid to one, two, or more nozzle-sections. The plate is also furnished with seats for the individual valves controlling the 110 passage of motive fluid to the buckets. The nozzles and valves are mounted within a valve-chest 12, the latter being provided with a cover 13, containing valve-rod packings 14. The valve-chest and its cover are 115 secured in place by bolts 15. Extending through the head of the valve-chest are as many valve stems or rods as there are groups of valves. In the present instance two of 120 these valve rods are shown; but a greater or 125 130

less number can be employed, if desired. On the inner end of each valve-rod is provided a suitable means for actuating the valves, which will be referred to later. Bolted to the casing of the turbine and extending substantially parallel with the shaft is a frame 17, that is provided with a jaw or fork at its outer end to receive the bearing 18, the said bearing being provided with trunnions on opposite sides.

Mounted in the trunnion-bearing is a lever 19, Fig. 1, which is attached to the tubular rod 20, that in turn is connected to the motor-piston 21, located within the cylinder 22. As the piston reciprocates the lower end of the lever 19 is moved about the axis of the bearing-trunnions as a center. Mounted on the lever 19 is a ball 23, as shown in Fig. 7. This ball is located within a yoke 24 and engages a spherical surface thereon and is retained in place by a nut 25. The yoke has a compound movement. It swings to and fro with the lever 19, and it is also given a rocking motion around the axis of said lever 19. This rocking motion is for the purpose of actuating the valve-stems successively. If it were not for an arrangement of this kind or an equivalent thereto, any movement of the motor-piston would impart corresponding movements to all of the valve-stems connected to the yoke. This matter will be more fully explained hereinafter. The motor-cylinder is supported in any suitable manner at any desired point and is provided with a detachable head 26, having a central orifice to receive the piston-rod and also to receive the packing 27. The packing can be adjusted by means of a gland-nut 28. The outer end of the piston-rod is connected to the lever 19 through a suitable connection, which permits the piston-rod to reciprocate freely. Both the piston and the rod are bored centrally to receive the reciprocating relay or pilot-valve 30, which controls the motor and is connected to the lever 5 and to the speed-responsive device by the adjustable link 35. A collar on the valve-spindle acting through lost motion on the sleeve 29 permits the valve to move the necessary amount, yet prevents it from moving too far.

Referring to Fig. 2, 8 represents the casing of the wheel, 36 the cover of the peripheral buckets, and 10 the nozzle-passages which discharge motive fluid against the wheel-buckets. Bolted to the nozzle and to the casing is a flat plate 11 containing a number of openings registering with openings or bowls formed in the nozzle. Each one of these openings is provided with a valve for controlling the admission of motive fluid to the nozzle-sections. The valves are marked 37, 38, 39, and 40. Valves 37 and 38 are united by lever 41 to form a pair, and valves 39 and 40 are united by the lever 42 to form a second pair. It is to be noted that the dis-

tance between the pivot 53 and the pivotal attachment of the lever to the valve 37 is less than the distance between the pivot 53 and the point of attachment of the valve 38. The object of this unbalanced arrangement is to insure the valve 37 opening before the valve 38. A similar arrangement is provided for the valves 39 and 40, so that the valve 39 will open before the valve 40 and close after it. The valve-rods 16 and 43 are each provided with a detachable head 44 on the inner end that is pivotally connected to the valve-carrying levers. The rods pass through suitable stuffing-boxes and at their outer ends pass through cylindrical guides 45. The guides are supported by a frame extension 46, that may be formed integral with the valve-chest or separable therefrom and retained in place by bolts. 19 represents the lever for actuating the valves, 24 the yoke, and 25 the nut carried by the yoke and engaging with the ball on the lever 19. On the valve-rods are collars 47, through which pass the bolts 48 and 49, the upper end of the yoke being pivotally attached to a valve-rod by the bolt 49, while the lower end is slotted to receive the bolt 48. This arrangement permits freedom of movement. During the time that the upper valve-rod is moving the bolt 48 acts as the pivot for the yoke, and while the upper rod is stationary and the lower one is moving the bolt 49 acts as a pivot; but said pivot instead of being located in the position shown has been moved slightly to the right because the upper valves are open, as will appear hereinafter. The distance between the point of intersection of the axes of the lever 19 and ball 23 and the pivot 48 is greater than the distance between it and the pivot 49. The object of this arrangement is to insure the opening of the valves 37 and 38 before the opening of the valves 39 and 40. In other words, unbalanced equalizing-levers are employed, and assuring the valves to be of equal area the valve or group of valves fastened to the short arm will open before the valve or group of valves fastened to the long arm. The exact proportioning of the parts is a matter of considerable importance, and as the number of valves in a group increases, say, to four or eight, it becomes even more important. This will be seen from the fact that the question of which valve will open next is determined, not by the proportions of any one lever, but by the product of the multiplication of motion derived from each lever in the group by that derived from each preceding one. The valve in which this multiplication is least will open first, that in which it is slightly greater will open next, and so on. Assuming that the valves are to open in one, two, three, &c., order, the desired result will be obtained by making the degree of unbalancing in the first lever some- 130

what greater than that in the two second levers, and this is in turn greater than that in the four levers of the third group, assuming that a third is used.

5 If the valve-stems are so disposed that the steam urges them in the same direction in which it urges the valves when closed, the arrangement just outlined serves the purpose of establishing a preference in the order 10 of closing as well as in the order of opening, providing each valve-stem comes out through a separate packing-box. If the valve-stems are arranged so that the pressure on the valves when open is in a direction opposite to that when they are closed, some other means will have to be employed for establishing the order of closing. Where the equalizing-lever is carried entirely in the steam-space, a spring may be used to establish a preference between the two valves in closing.

15 I have stated that the valves open in one, two, three, four order and close in the reverse. This may be modified, if desired, but 20 the nozzle-sections in service should be adjacent to each other.

25 A separate selective or escapement device 30 may be substituted for the unbalance in the equalizing-levers, or it may be supplementary to this. In its most complete form it establishes the order both of opening and of closing regardless of unbalance. Instead of a complete selective or escapement device a partial one may be used, which may determine the 35 order of opening, but not of closing, or vice versa.

It is to be noted that the unbalanced relation of the valves and the actuating-levers of itself constitutes a selective device, and 40 the broad claims are to be interpreted with this in view.

45 One form of a selective or escapement device comprises a hook 51, which is adapted to enter into engagement with a stop 52, located 50 within the valve-chest. The second valve rod or stem and also any succeeding valve-rods will be provided with the same or equivalent means. Referring to Fig. 13, the construction and arrangement of these parts 55 will be readily understood. 37 and 38 represent a pair of valves which are connected by a lever 41. This lever is in turn attached to the head 44 on the end of the valve-rod 43 by means of the pivot 53. The valve 37 is secured to the lever by a pivot 54 and the valve 38 by the pivot 55. Formed integral 60 with the lever 41 or otherwise secured thereto is a hook 51, that is adapted to engage with and be seated on a stop 52, that is bolted 65 to one of the inner walls of the valve-chest. Assume that the parts are in the position shown. The steam or other elastic fluid contained in the valve-chest will act with the same or substantially the same force on 70 each of the valves. Therefore when the valve-

70 rod starts to move in the direction of the arrow the valve 37 will open first, because the distance between the pivots 53 and 54 is less than the distance between the pivots 53 and 55. In other words, the force exerted 75 on the valve 37 is greater than the force exerted on the valve 38. During the interval that the valve 37 is moved from its seat the pivot 55 is acting as a fulcrum for the lever 41. After the hook 51 moves upward a certain distance its upper surface will engage a shoulder 56, formed on the stop 52. Continued motion of the valve-rod 43 in the same direction will cause the end of the hook to slip into the slot 57 and act as a stop for 80 the lever 41. As the movement of the rod continues the valve 38 will open against the pressure of the fluid-pressure within the valve-chest. As shown, the valves in each group or pair have the same area, and 85 reliance is placed upon the arrangement of the parts to insure the successive opening of the valves; but I may construct the valve, as in Fig. 24, with unequal areas, so that one will open before the other. I prefer, however, to use a mechanical arrangement on account of its greater reliability. The arrangement of the hooks, levers, or unequal areas forms what may be termed a "selective" or "escapement" device for the valves 90 in each group.

95 The arrangement thus far described is satisfactory to insure the opening of the valves 37 to 40 in one, two, three, four order when there is pressure in the steam-chest. To insure the proper closing of the valves at all times, a second selective device is provided, which is so constructed and arranged that it 100 always insures the closing of the valves 40 and 39 prior to the closing of the valves 38 105 and 37. This arrangement is desirable for several reasons, the principal being that whatever valves are open should be contiguous—that is to say, a closed nozzle-section should not intervene between two open ones. 110 Again, the valve 40 controls more nozzle-sections than the other valves, and it should therefore be the last to open and the first to close. When the load on the turbine forms a substantial part of its total capacity, the 115 amount of fluid admitted or cut off by a single valve can with advantage be made somewhat greater than under light-load conditions, since the percentage of increase or decrease with respect to the total amount of fluid being supplied is less with a heavy load condition than with a light. By increasing the total number of nozzle-sections under control of a given valve the total number of valves required to control the turbine is reduced. Hence the governing mechanism can be simplified and arranged to occupy a smaller space. A decrease in the number of valves decreases the cost of manufacture and 125 of maintenance.

In the drawings I have shown as an example one form of selective device for determining which group of valves shall operate first; but this can be modified without departing 5 from the spirit of my invention. It comprises a stationary piece or hook 58, which is attached to the outside of the valve-chest, and a movable hook 59, that is carried by the yoke. These parts are so arranged that 10 when the valves 37 and 38 open the end of the hook 59 passes from the left-hand to the right-hand side of the end of the hook 58 and remains in this position during the time that valves 39 and 40 open without in any way, 15 however, affecting their operation. When the valves start to close, the valve 40 has to close first and then the valve 39. This is due to the upper valve-rod 43 being locked by the end of the hook 59 engaging with the flat 20 surface on the hook 58 and also to the relation of the leverages between the valves 39 and 40 and the valve-rod, as previously described. The upper valve-rod 43 being locked against movement by the selective device, 25 initial movement of the piston under these conditions (in Fig. 2 a movement toward the left) will cause the valve-rod 16 to depress the lever 42 until the valve 40 is seated, the hook 51 in the meantime remaining 30 in engagement with the stop 52. As soon as valve 40 is seated further movement of the rod 16 in the same direction will close or seat the valve 39. At or about the time the valve 35 39 closes, the hook 59 of the selective device clears the end of the hook 58, and continued movement of the lever 19 in the same direction will cause valve 38 to close and then the valve 37. The operation of these valves will be more clearly understood from the dia- 40 grammatic Figs. 8 to 11.

In Fig. 8 the difference in leverage between the axis of the lever 19 and the pivots 48 and 49 is clearly shown, the line 60 being shorter than the line 61. The valves in Fig. 8 are 45 shown in a closed position. Assume now that the upper valve-rod 43 is moved in the direction of the arrow, the lower one remaining stationary, with the pivot 48 acting as a fulcrum for the cross-head 24. This results 50 in moving the parts into the position shown in Fig. 9—*i. e.*, the valve 37 is open and the hook 51 is acting as a stop. Continued movement of the upper valve-rod 43 in the same 55 direction moves the parts into the position shown in Fig. 10, and the hook 59 of the selective device is now in engagement with the right-hand end of the hook 58, and both valves 37 and 38 are open. Continued motion of the lever 19 in the same direction 60 causes the valve-rod 16 to start into motion, the pivot 49 acting as a fulcrum for the cross-head. As shown in Fig. 11, this results in the opening of valve 39, valves 37 and 38 remaining open. In Fig. 12 all four of the 65 valves are shown in the open position and

the end of the hook 59 is resting on the right-hand end of the hook 58, so that when the motion of the lever 19 is reversed the lower rod 16 will be first affected and then the upper rod 43. 70

A combination of unbalanced levers and selective or escapement devices possesses the advantage that the sequence of operation is positive and the strains and wear on the parts reduced to a minimum. Under normal conditions this sequence is established by the unbalanced levers alone, and therefore the selective devices or hooks are not subjected to any noticeable amount of wear when the valves open. 80

Referring now to Figs. 4 to 6, inclusive, and 15 and 16, the construction and operation of the motor for actuating the valves and the valve for controlling the motor will be described. 21 represents the motor-piston located in a cylinder 22 of suitable construction. The end of the cylinder is closed by a head 26, through which the tubular end 20 of the piston-rod extends. Fluid is at all times flowing through the cylinder. It enters by the conduit 62 and leaves by the conduit 63. The piston is provided with a radial passage or port 64, which is at all times in communication with the inlet-pipe 62, and the position of the valve 30 within the piston 95 determines whether or not the piston will stand still or move to the right or the left. 90

As shown in Fig. 4, the valve is so set that the piston is supposed to be in the act of moving to the right. Under these conditions the 100 passage of fluid is as follows: Fluid enters by the pipe 62, flows through the port or passage 64 into the chamber 65, surrounding the left-hand end of the valve, from which it flows through a radial passage into an axially- 105 extending passage 66, discharging into the cylinder-space at the left-hand end of the piston. This relation of parts will with fluid under pressure entering the pipe 62 tend to start the piston and attached parts into operation; but until a free passage is provided on the right-hand side of the piston this action cannot take place. In other words, the exhaust-passage must be open. 110

On referring to Fig. 5 it will be seen that 115 the valve 30, controlling the admission-port, also controls the exhaust-port, and the passage of fluid under these conditions is as follows: Assume that the piston has a tendency to move to the right, due to the position of the valve. A pressure is created in the left-hand end of the cylinder and fluid flows from the right-hand end of the cylinder-space through the axially-extending passage 67, thence through the radial passage located between the chamber 68 and the left-hand end of the valve 30. From here it passes through a central opening in the valve and is discharged into the space 69, which communicates with the axially-extending passage 70, 120 125 130

the latter being in uninterrupted communication with the radial passage 71 and discharge-port 72. In order to reduce the tendency to leakage between the piston and the valve to the atmosphere, the groove 73 is provided, which is in constant communication with the exhaust side of the piston. From the arrangement described it will be seen that if a given quantity of fluid be admitted to the cylinder a corresponding amount of fluid is discharged. Hence the flow is uninterrupted.

The next point to be considered is how the flow of lubricant through the cylinder is maintained when the valve 30 is in its stationary or normal position. This will be apparent from Fig. 15, which is a drawing on an enlarged scale of the valve mechanism. Referring to this figure, 30 represents the valve in a normal or central position, so that the passage of fluid through the piston and cylinder is free or unrestricted. Fluid is admitted by the inlet-pipe 62 and radial passage 64 (shown in dotted lines) to the chamber 65, which, as has been before pointed out, is always connected to the inlet side of the system. The enlargement or head at the left-hand end of the valve is situated opposite the port or passage communicating with the chamber 68, and it is to be noted that the width of this port is greater than the width of the head. Hence the fluid has a relatively free passage from the inlet-chamber 65 into the chamber 68, and the latter is in free communication with the central opening in the valve. The central opening communicates with the exhaust-chamber 69, and the latter in turn discharges in the chamber 70, the radially-extending passage 71, and the exhaust-passage 72. It is also to be noted that the middle projection or head on the valve 30 is directly opposite the radially-extending passage 74, so that fluid under the inlet-pressure can pass around it, as shown by the dotted arrow, into the exhaust-chamber 73, and since the passage 74 is in communication with the cylinder-space at the left-hand end of the piston, as shown in Fig. 4, it follows that the piston is practically balanced and will therefore stand still. It will also be seen that the fluid flows through parallel or multiple paths. The area of the piston at the left-hand end is somewhat greater than the area of the piston on the right-hand end, owing to the valve and piston-rod, and there is a slight tendency for the piston to always move to the right, which tendency is opposed by the speed-governor. As the speed-responsive device moves the lever 5 in one direction or the other the position of the valve 30 is changed and fluid is admitted to one side of the piston or the other, and movement of the piston imparts a corresponding movement to the lever 19 and thence to the valve-rod 43 and 16. When the number of

valves open is sufficient to supply exactly the amount of steam or other elastic fluid required by the turbine, the valve 30 will occupy its normal or intermediate position and the valve-actuating lever 19 and the piston will remain stationary; but when the fluid supplied by any given number of valves is a little greater or a little less than is required at least one valve will be opening and closing for regulating purposes. In case the supply of fluid to the cylinder fails a spring may be employed to move the piston, and the latter will move the valves to their closed or safety position. If at any time the speed of the turbine becomes abnormally great, the lever 5, acting through the link 35 on the valve 30, will press directly on the piston in a direction to cause it to close the valves. This is due to the fact that the left-hand end of the valve is arranged to engage the head of the piston when the parts are moved to the position shown in Fig. 1. The parts are so arranged that the piston follows the valve to establish a position of equilibrium. Under normal conditions of operation the valve will not stand exactly central, as in Fig. 15, but a little to one side thereof.

It is necessary in any relay mechanism to provide a device by which when the member determining the movement performs a certain excursion bringing into action the power for moving some more ponderous mechanism the movement thereby determined shall of itself shut off the source of power to the moving member as soon as it reaches a limit corresponding to the movement of the relay or pilot that started it into motion. It is essential with whatever form of actuator is used with the valve-gear that the action just referred to shall take place. In the structure illustrated the action is accomplished in a very simple manner by having the motion of the pilot-valve the same in direction and amount as the motion of the piston which it controls, and, further, by mounting the pilot-valve in the motor-piston a movement of the pilot-valve will cause the piston to start in the same direction and travel until it has exactly overtaken the valve and again established a relation of equilibrium.

Referring to Figs. 17 to 21, inclusive, selector means are shown for determining the order of opening and closing of the valves, whether the steam-chest is under pressure or not. 16 and 43 indicate the valve-operating rods, as before. In addition to the hook 51 each pair of valves is provided with a hook 80, that engages with the stop 81, located inside of the valve-chest or is carried by a suitable fixed support. A hook 82 is also provided that is adapted to engage with the hook 83, carried by the yoke 24. In Fig. 17 all of the valves are shown in the closed position and the hooks 82 and 83 are in engagement. A movement of the rod 43 to the

right will first open valve 37. The hook 80, being in engagement with the stop 81, holds the valve 38 against its seat until after the valve 37 is fully opened. Continued movement of the rod 43 to the right will then disengage the parts 80 and 81 and open the valve 38. The hooks 58 59 and 82 83 then assume the position shown in Fig. 18. As soon as the hook 59 assumes the position shown in Fig. 19 the lower end of the yoke 24 is moved to the right by the lever 19 and the hooks 82 and 83 pass out of engagement. In Figs. 20 and 21 the different positions of the hook 80 are clearly shown.

In Fig. 22 the invention is shown in connection with the step-bearing 84 of a vertical-shaft turbine. 85 represents a suitable high-pressure pump that is driven by the power-shaft 86. Fluid from the pump enters the cylinder 22 of the motor, from which it flows continuously through the conduit 87 to the chamber 88 in the step-bearing. The exhaust-lubricant from the bearing flows through the conduit 89 to the tank or receptacle 90, the latter being connected to the suction side of the pump.

The practical operation of my improved governing mechanism showed that under certain conditions there was a slight tendency when the speed-responsive device was adjusted close to isochronism for the relay or pilot valve 30 to hunt. This was found to be due to the "friction of repose." In other words, when the valve and piston were at rest a certain amount of opposition due to friction was present which opposed any tendency to movement. It first retarded the movement of the relay-valve relative to the piston, and later it retarded the movement of the piston in over-taking the valve. To overcome this, I provided an arrangement which periodically destroyed the friction of repose. This can be done in a number of ways, the one employed by me being very simple. A gear-pump was substituted for the plunger-pump of Fig. 22 and arranged to supply fluid under pressure to the motor or actuator, and in one of the teeth was a small hole or passage 91, as shown in Fig. 25. At every revolution of the gear there was a slight leak, and this in turn changed the back pressure on the end of the valve 30 and caused it to jump slightly once every revolution. This arrangement worked with entire satisfaction.

In the operation of the mechanism there is a tendency for the pressure in the cylinder to force the valve 30 outward, thus aiding the spring of the speed-responsive device and raising the speed at which the governor will act. This renders it possible to adjust the speed of the machine by using on the discharge-pipe 63 of the motor a throttle or similar valve 92, Fig. 22, capable of adjusting the back pressure. This will permit of

synchronizing the speeds of separate machines for parallel operation.

In accordance with the provisions of the patent statutes I have described the principle of operation of my invention, together with the apparatus which I now consider to represent the best embodiment thereof; but I desire to have it understood that the apparatus shown is only illustrative and that the invention can be carried out by other means.

What I claim as new, and desire to secure by Letters Patent of the United States, is—

1. The combination of a prime mover, a regulating-valve, a motor comprising a piston and a cylinder for operating the valve, and a valve controlling the motor which permits fluid to flow continuously through the motor.

2. The combination of a prime mover with a regulating-valve, a motor comprising a piston and cylinder for operating it, a valve controlling the motor, and ports in the motor controlled by the valve through which fluid flows continuously.

3. The combination of a prime mover with a regulating-valve, a motor comprising relatively movable elements for moving the valve, a controlling-valve carried by one of said elements for regulating the flow of liquid through the other element, and inlet and discharge ports formed in the said element which are controlled by the valve.

4. The combination of a prime mover with a regulating-valve, a fluid-pressure motor for moving the valve comprising a piston and cylinder, the former normally occupying an intermediate position in the latter, conduits for continuously delivering and receiving fluid from the cylinder, a passage which normally conveys fluid around the piston, and a valve which interrupts the continuity of this passage when it is desired to impart relative movements to the piston and cylinder.

5. In combination a prime mover, a number of separately-actuated governing devices, a motor for actuating them comprising a piston and cylinder through which fluid flows continuously, and a pilot-valve for modifying the passage of fluid when it is desired to move the governing devices.

6. In combination a prime mover, a number of separately-actuated regulating devices for controlling the prime mover, an actuator for the devices which may move them otherwise than in a predetermined order, and a connection between the motor and the regulating devices which includes a means that establishes a preference as to the order of operation of said devices.

7. In combination a prime mover, a number of separately-actuated regulating devices for controlling the prime mover, an actuator for the devices which may move them otherwise than in a predetermined order, a con-

nection between the actuator and the devices which includes a means that establishes a preference as to the order of operation of said devices, and a device responsive to load changes on the prime mover for controlling the actuator.

8. In combination a prime mover, a number of regulating-valves therefor, an actuator for the valves which may move them otherwise than in a predetermined order, and a means intermediate the valves and actuator for insuring the opening of the valves in the proper sequence.

9. The combination of a prime mover with a governing mechanism comprising a plurality of separately-actuated valves, a motor for operating the valves which may move them otherwise than in a predetermined sequence, and a selective device which definitely determines the order in which the valves will operate.

10. The combination of a prime mover with a governing mechanism comprising a number of valves arranged in groups, a selective device which determines the order in which the valves shall operate, a source of motive power for actuating the valves, and a selective device which determines the order of operation of the different groups.

11. The combination of a prime mover with a governing mechanism comprising valves arranged in groups, an actuator common to the groups, and a selective device which determines the order of operation of the different groups.

12. The combination of a prime mover with a governing mechanism comprising valves, a support that is bodily movable to which the valves are attached, and a selective device which determines the movement of said support and consequently which valve is to be operated.

13. The combination of a prime mover with a governing mechanism comprising separate valves, a lever to which the valves are connected, a power-actuated device for moving the lever, and a means which determines the order of operation of the valves.

14. In a governor, the combination of a number of separately-actuated valves, a lever connecting the valves, and an actuator or motor for moving the lever, the lever and valves being so related that the actuator or motor operates them successively.

15. In a governor, the combination of a number of separately-actuated valves, a single motor which operates them, and an unbalanced connection between the motor and the valves for making the operation successive.

16. In a governor, the combination of a number of separately-actuated valves, a single motor which operates them, an unbalanced connection between the motor and the valves for making the opening successive,

and a selective device for insuring the closing of the valves in the reverse order of their opening.

17. In a governor, the combination of groups of valves, a single motor for operating the valves of the groups, a device for determining the order in which the groups shall operate, and a device for determining the order in which the valves in the groups shall operate.

18. In a governor mechanism, the combination of a number of mechanically-operated regulating-valves, a single motor for opening and closing the valves which may move them otherwise than in a predetermined order, and a selective means for insuring the opening and closing of the valves one after the other in a predetermined sequence.

19. In a governor mechanism, the combination of a plurality of valves arranged in pairs, a single motor for actuating all of the valves, and selective means for determining which pair of valves is to be operated to meet a certain condition and also which valve of the pair.

20. In a governing mechanism, the combination of a number of valves, a lever, a motor connected thereto, and a yoke receiving movement from the lever and imparting it to the valves.

21. In a governing mechanism, the combination of a number of valves, a lever, a motor connected thereto, a yoke pivotally supported by the lever, and connections between the yoke and the valve.

22. In a governor mechanism, the combination of a number of nozzle-passages, a number of individual valves for controlling the passages, which is less than the number of said passages, one of said valves controlling a greater number of passages than the others, and a motor for operating the valves in a predetermined sequence.

23. In a governor mechanism, the combination of a plurality of nozzle-passages divided into groups of unequal numbers, individual valves controlling the passage of fluid to said groups, and a motor for operating more than a single valve.

24. In a governor mechanism, the combination of a plurality of nozzle-passages divided into groups, one of said groups containing more passages than another and arranged to come in service under heavy-load conditions, a valve for each group, and a motor common to the valves for actuating them one after the other.

25. In a governor mechanism, the combination of a plurality of nozzle-passages arranged in groups, a plate located adjacent to the bowls of said passages and provided with valve-seats and orifices, a valve-chest, and valves in the chest arranged to engage the seats on the plate.

26. In a governor mechanism, the combi-

nation of a plurality of discharge-passages, individual valves controlling the passages, a chest containing the valves, and selective devices located within the chest for determining the order in which the valves operate.

27. In a governor mechanism, the combination of a plurality of controlling-valves arranged in groups, a chest containing the valves, a means located outside of the chest for actuating the valves, a selective device located within the chest for determining the order of operation of the valves in a group, and a selective device located outside of the chest for determining the order of operation of the groups.

28. In a governor mechanism, the combination of a plurality of valves, rods for actuating the valves arranged in parallel relation, a yoke for moving first one rod and then the other, and a motor for moving the yoke.

29. In a governor mechanism, the combination of a valve, a motor for actuating the valve through which fluid flows continuously, and a speed-responsive means that controls the movement of the motor.

30. In a governor mechanism, the combination of a valve, a motor for actuating the valve, through which fluid separate from that controlled by the valve is flowing continuously, a valve for regulating the action of the motor, and a speed-responsive device that moves the motor-regulating valve in response to speed changes.

31. In a governor mechanism, the combination of a number of regulating-valves, a motor for actuating the valves in a predetermined order, through which fluid is continuously flowing, a valve for modifying the passage of fluid through the motor so as to cause relative movements of the motor elements, a speed-responsive device, and a connection for imparting motion from the device to the motor-controlling valve.

32. In a governor mechanism, the combination of a number of regulating-valves, a motor for actuating them comprising a hollow piston and cylinder through which fluid under pressure flows continuously, a valve located in the movable part of the motor which modifies the path of the fluid, the said valve occupying a central position when the piston and cylinder are stationary with respect to each other and a position at one side of said central position when the piston and cylinder are moving with respect to each other, and a speed-responsive device for moving the valve.

33. In a governor mechanism, the combination of a number of admission-valves, a lever for operating them which has a single plane of movement, a reciprocating motor for moving the lever, and a yoke for operating the valves which has a movement in a plane at right angles to that of the lever.

34. In a governor mechanism, the combination of a number of admission-valves, a lever, a reciprocating motor for moving the lever, a yoke pivotally mounted on the lever, pivots for the yoke disposed on opposite sides of its axis, and rods carrying the pivots for the yoke which are connected to the valves.

35. In a governor mechanism, the combination of a number of admission-valves, a lever, a motor for moving the lever, a yoke mounted on the lever, connections between the yoke and the valves, and a controlling device for the motor.

36. In a governor mechanism, the combination of a number of admission-valves, a lever, a motor for moving the lever, a yoke mounted on the lever, connections between the yoke and the valves, and selective devices which determine the order of operation of the valves.

37. In a governing mechanism, the combination of a pair of valves, a lever connecting the valves in a manner to exert unequal leverages thereon, and an actuator for moving the lever.

38. In a governing mechanism for a prime mover, the combination of a number of valves, a lever connected to the valves in a manner to exert unequal leverages thereon, and a motor responding to changes in speed of the prime mover.

39. In a governing mechanism, the combination of a number of regulating devices, a lever connected to each of the devices, and means for causing the lever to actuate the said devices one after the other.

40. In a governing mechanism, the combination of valves arranged in pairs, a lever connecting each pair and exerting unequal leverages thereon, a yoke connecting the separate levers and exerting unequal leverages thereon, and a motor for moving the yoke.

41. In a governing mechanism, the combination of valves arranged in pairs, a connection between the valves of each pair, a yoke uniting said connections, a motor for operating the yoke, and a selective device which determines the order of operation of the valves.

42. In a governing mechanism, the combination of valves arranged in pairs, a connection between the valves of each pair, a yoke uniting said connection in a manner to exert unequal leverages thereon, a motor for moving the yoke, and a selective device which insures the opening of the valves in a predetermined sequence and their closing in the reversed order.

43. In a governing mechanism, the combination of a number of valves, a reciprocating motor for operating them, the piston of which is unbalanced as to areas, a valve for modifying the continuous flow of fluid through the motor, and a speed-responsive device that actuates the motor-valve.

44. In a governing mechanism, the combination of a number of valves, a motor for actuating them comprising a fixed and a moving element, a valve for controlling the action of said moving element, the moving element being so arranged that it follows the valve, and a speed-responsive device for moving the valve.

45. In a governing mechanism, the combination of an admission-valve, a motor for actuating it comprising a hollow piston and a cylinder, ports or passages in the piston arranged in multiple, a valve carried by the piston which controls the flow of fluid through said ports, and a device for moving the motor-valve.

46. In combination, a prime mover having a bearing, a valve for controlling the passage of motive fluid through the prime mover, a motor for actuating the valve comprising a piston and cylinder through which fluid flows continuously from a source of supply to the bearing, and a valve for modifying the passage of fluid through the motor to the bearing without interrupting the continuity of its flow.

47. In combination, a prime mover having a bearing, a valve for controlling the passage of motive fluid through the prime mover, a motor for actuating the valve, comprising a piston and cylinder through which fluid flows continuously from a source of supply to the bearing, a valve for modifying the passage of fluid through the motor to the bearing without interrupting the continuity of its flow, and a speed-responsive device that moves the valve in accordance with speed changes.

48. In combination, a prime-mover having a bearing, a valve for controlling the passage of motive fluid through the prime mover, a motor for actuating the valve through which lubricant flows continuously to the bearing, a valve which modifies the passage of lubricant through the motor to cause the motion of the motor-piston, a means tending at all times to cause the motor to close the valve regulating the passage of motive fluid to the prime mover, and a speed-responsive device that actuates the motor-controlling valve.

49. In a governing mechanism, the combination of a regulating-valve, a motor for operating it, through which fluid flows continuously, a valve controlling the passage of fluid through the motor which admits the same amount of fluid to one end of the cylinder that is discharged at the other thereby keeping the flow constant, and a speed-responsive device for actuating the motor-valve.

50. In a governing mechanism, the combination of a plurality of individual valves regulating the passage of motive fluid into the

same stage, and a motor for operating the valves in pairs.

51. In a prime mover, the combination of relatively movable elements, a governing mechanism therefor, and a means for nullifying the effects of the friction between parts of the governor mechanism.

52. In a prime mover, the combination of relatively movable elements, a governing mechanism therefor, and a means that comes into service periodically which nullifies the effects of friction between parts of the governor.

53. In a prime mover, the combination of relatively movable elements, a governing mechanism therefor which responds to changes in fluid-pressure, and a means for suddenly and temporarily changing the pressure to nullify the effects of friction between the parts of governing mechanism.

54. The combination of a prime mover with a hydraulic governing mechanism including a plurality of separate and successively-acting valves, and a valve for adjusting the governing mechanism by varying the fluid-pressure therein.

55. A prime mover and a hydraulic mechanism for governing its speed including a plurality of separate and successively-acting valves, in combination with a valve which varies the back pressure of the hydraulic mechanism for synchronizing purposes.

56. The combination of a prime mover, a regulating-valve therefor, an abutment for actuating the valve which is capable of assuming intermediate positions, and a pilot-valve for controlling the movements of the abutment, the said valve being located in the abutment and capable of assuming intermediate positions to control it.

57. The combination of an apparatus to be controlled, with independent regulating devices therefor, an actuator for moving the regulating devices in response to changes in operating conditions, the relation between the regulating devices and actuator being such that the former may operate otherwise than in a given order, and a means that establishes a preference as to the order of operation of said devices.

58. In a governing mechanism, the combination of regulating devices, a lever connecting the devices in a manner to exert unequal leverages thereon, and a means responsive to variations in load for moving the lever.

In witness whereof I have hereunto set my hand this 12th day of September, 1904.

JOHN G. CALLAN.
